(57) **CLAIM**

The ornamental design for a surgical robotic device, as shown and described.

DESCRIPTION

FIG. 1 is a back perspective view of a first embodiment of a surgical robotic device;

FIG. 2 is a front perspective view of the first embodiment of the surgical robotic device illustrated in FIG. 1;

FIG. 3 is a front view of the first embodiment of the surgical robotic device illustrated in FIG. 1;

FIG. 4 is a back view of the first embodiment of the surgical robotic device illustrated in FIG. 1;

FIG. 5 is a right view of the first embodiment of the surgical robotic device illustrated in FIG. 1;

FIG. 6 is a left view of the first embodiment of the surgical robotic device illustrated in FIG. 1;

FIG. 7 is a top view of the first embodiment of the surgical robotic device illustrated in FIG. 1;

FIG. 8 is a bottom view of the first embodiment of the surgical robotic device illustrated in FIG. 1.

FIG. 9 is a back perspective view of a second embodiment of a surgical robotic device;

FIG. 10 is a front perspective view of the second embodiment of the surgical robotic device illustrated in FIG. 9;

FIG. 11 is a front view of the second embodiment of the surgical robotic device illustrated in FIG. 9;

FIG. 12 is a back view of the second embodiment of the surgical robotic device illustrated in FIG. 9;

FIG. 13 is a right view of the second embodiment of the surgical robotic device illustrated in FIG. 9;

FIG. 14 is a left view of the second embodiment of the surgical robotic device illustrated in FIG. 9;

FIG. 15 is a top view of the second embodiment of the surgical robotic device illustrated in FIG. 9; and,

FIG. 16 is a bottom view of the second embodiment of the surgical robotic device illustrated in FIG. 9.

(Continued)

The portion of the article depicted in broken lines is for illustrative purposes only and forms no part of the claimed design.
